UNITED STATES PATENT OFFICE

ERNEST H. HINRICH, OF BALTIMORE, MARYLAND

DENTAL CASTING MACHINE

Application filed July 18, 1932. Serial No. 623,245.

This invention relates to new and useful improvements in dental casting machines of the centrifugal type including a swinging or shiftable holder for the mold or crucible and has for its primary object to provide, in a manner as hereinafter set forth, a machine of this character embodying a novel construction, combination and arrangement of parts through the medium of which the holder will 10 be moved toward a position in alinement with the rotary support substantially simultaneously with the beginning of rotary movement of said support or immediately thereafter.

Other objects of the invention are to provide 15 a dental casting machine of the aforementioned character which will be simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a dental casting machine constructed in accordance with the present invention.

Figure 2 is a view in vertical longitudinal section through the machine, showing same in operation.

Figure 3 is a view in top plan of the device.

Figure 4 is a detail view in transverse section, taken substantially on the line 4—4 of Figure 1.

Figure 5 is a detail view in perspective of the rotary support.

Figure 6 is a detail view in vertical transverse section taken substantially on the line 6—6 of Figure 1.

Referring now to the drawings in detail, it will be seen that the embodiment of the 45 invention which has been illustrated comprises a support which is designated generally by the reference numeral 1, said support being fixed by a set screw 2 on the shaft 3 of an electric motor 4 for rotation in a vertical plane, the support being provided with a

transverse opening at an intermediate point for the reception of the shaft 3. The electric motor 4 is provided with a supporting standard 5 but may be mounted in any other suitable manner. The support 1 which has been 55 illustrated includes a bar 6 from one end of which a pair of spaced, parallel arms 7 extend providing a fork, said arms 7 having openings 8 in their free end portions the purpose of which will be presently set forth. 60 Projecting laterally from one of the arms 7 is a stop 9, the purpose of which also will be presently set forth.

Mounted for swinging movement between 65 the arms 7 of the support 1 is a mold or crucible holder which is designated generally by the reference numeral 10, said holder 10 including a flat plate 11 constituting a bottom from which spaced fingers 12 extend substantially at right angles. Trunnions 13 project outwardly from an opposed pair of the fingers 12 and are journaled in the openings 8 of the arms 7. A crank arm 14 extends substantially at right angles from the outer end of one of the trunnions 13 and terminates in 75 an eye 15.

The reference numeral 16 designates a rod which is slidably mounted in a supporting guide 17 on the support 1 and has one end 80 pivotally connected with the eye 15 on the crank arm 14. The other end portion of the rod 16 projects beyond the corresponding end of the support 1 and is threaded, as at 18, and has threadedly mounted thereon for longitudinal adjustment a counterweight 19. 85

The reference numeral 20 designates the mold or crucible in position in the holder 10. The mold or crucible 20 is provided with a concavity 21 in its top for the reception of the molten metal 22. It will be noted that the metal 22, by reason of the construction and arrangement provided, is substantially 90 in alinement with the axis upon which the holder 10 swings.

In operation, when the support 1 begins 95 to rotate, or immediately thereafter, the weight 19 is caused to move outwardly relative to said holder 1 by centrifugal force, causing the holder 10 with the mold or crucible 20 therein to be swung toward a position 100

in alinement with said support 1. By thus immediately swinging the holder 10 outwardly toward a position in alinement with the support 1, spilling of the molten metal from the mold or crucible 20 when said support 1 begins to rotate is avoided. The stop 9 is disposed in the path of the crank arm 14 for limiting the swinging movement of the holder 10 under impulsion by the weight 19.

10 It is believed that the many advantages of a dental casting machine constructed in accordance with the present invention will be readily understood, and, although a preferred embodiment of the invention is as illustrated and described, it is to be understood that changes in the details of construction and in the combination and arrangement of parts may be resorted to which will fall within the scope of the invention as claimed.

15 20 What is claimed is:

1. A casting machine comprising a rotary support, a holder pivotally mounted for swinging movement on the support, and means mounted on the support and operatively connected to the holder for swinging said holder on the support when said support is actuated.
2. A casting machine comprising a rotary support, a holder pivotally mounted on the support, a weight shiftably mounted on the support, and means operatively connecting the holder to the weight for actuation by said weight.
3. A casting machine comprising a rotary support, means for rotating the support, a holder pivotally mounted on the support on one side of the axis of rotation of said support, and means mounted on the support on the other side of the axis of rotation of said support and operatively connected to the holder for swinging said holder on the support when said support is rotated.
4. A casting machine comprising a rotary support, means connected with an intermediate portion of the support for rotating said support, a holder pivotally mounted on the support on one side of the axis of rotation of said support, and means shiftably mounted on the support on the other side of the axis of rotation of said support and operatively connected to the holder for swinging said holder on the support when said support is rotated.
5. A casting machine comprising a rotary support, means connected with an intermediate portion of the support for actuating

said support, a holder pivotally mounted on the support for swinging movement on one side of the axis of rotation of the support, a weight shiftably mounted on the support on the other side of the axis of rotation of said support, and means operatively connecting the holder to the weight for actuation by said weight.

6. A casting machine comprising a rotary support, means connected with an intermediate portion of the support for actuating said support, a mold holder pivotally mounted on one end portion of the support, a weight shiftably mounted on the other end portion of the support, and means operatively connecting the holder to the weight for actuation by said weight.

7. A casting machine comprising a rotary support, means connected with an intermediate portion of the support for actuating said support, a mold holder pivotally mounted on one end portion of the support, a rod operatively connected to the mold holder and slidably mounted on the support, said rod extending adjacent the other end of the support, and a weight mounted on the rod adjacent said other end of the support, said weight constituting means for actuating the holder toward a position in alinement with the support when said support is rotated.

8. A casting machine comprising a rotary support, means connected with an intermediate portion of the support for rotating said support, the support including a bar and further including spaced arms projecting from one end portion of the bar, said arms having openings in their free end portions, a mold holder, trunnions mounted on the mold holder and journaled in the openings for mounting the holder for swinging movement on one end portion of the support, a crank arm extending from one of the trunnions, a guide mounted on the other end portion of the support, a rod slidably mounted in the eye and connected, at one end, to the crank arm, and a weight adjustably mounted on the other end portion of the rod.

9. A casting machine comprising a rotary support, means for actuating the support, a holder pivotally mounted on the support, and centrifugal force responsive means operatively connected to the holder for swinging said holder on the support when said support is actuated.

In testimony whereof I affix my signature.

ERNEST H. HINRICHSEN.
